ELECTROPNEUMATIC BRAKE MECHANISM.

1,282,130.

Specification of Letters Patent.

Patented Oct. 22, 1918.

Application filed April 1, 1912. Serial No. 225,860.

To all whom it may concern:

Be it known that we, JAMES RICHARD SLOAN, HOWARD F. PERRY, and IRA V. GOODMAN, citizens of the United States, and residents of Altoona, in the county of Blair and State of Pennsylvania, have jointly invented an Electropneumatic Brake Mechanism, of which the following is a specification.

Our invention is an improved electro-pneumatic brake mechanism efficient in character, simple in construction, and simple in operation, which effects the following desiderata:

The brakes are operated in the manner desired by the combination with a pneumatic system, of a simple, inexpensive and easily operated electric system requiring the use of but a single train wire without special connections between the cars, the air and current being regulated to operate the brakes by the same movement.

The brakes on all the cars of a train, whether long or short, are applied simultaneously, thus permitting a stop to be made in shorter time under given conditions and avoiding the necessity for the usual degree of care in applying the brakes and the usual bunching of the cars with the risk of wrecks therefrom, the emergency application being made safely when traveling at a rate of speed which would frequently wreck a train equipped with the usual pneumatic mechanism.

The brakes can be released simultaneously on all the cars of a train, with the resulting advantage, for instance, that all such cars, when standing on a down grade, commence to roll simultaneously, the slack is taken up gradually and the violence is avoided which attends the operation of the usual pneumatic equipment whereby the cars are released in succession, due to the time required for the pneumatic impulse to travel back through the train, and the starting wave may pull out a draw head near the rear end of the train.

The engineer or operator on the locomotive or elsewhere is enabled to produce effects on the air brakes of the entire train exactly similar to the effects now produced by "setting up the retaining valves" on each car of the train.

The same operation that couples the sec-

tions of the brake pipe in making up a train couples the sections of the electric mechanism, and the same operation that closes the brake pipe as at the end of a train to render the air operative, also grounds the electric mechanism to produce an operative closed circuit, the ground connection being also opened by the operation which opens the pipe.

The mechanism is adapted for use successfully for the difficult service required on long freight trains, since it avoids the complications of construction and the seriously objectionable differences in the times of action of the brakes on the separate cars with the mechanisms heretofore used.

It is also adapted for convenient application to signaling between the ends of trains, having peculiar advantages in long trains, over former signaling systems.

The characteristic features and advantages of the invention are fully disclosed in the following description and the accompanying drawings, illustrating certain of the various forms in which the invention may be embodied.

In the drawings, Figure 1 is a diagrammatic view of mechanism embodying the invention; Fig. 2 is a broken part sectional view of a form of electro-pneumatic mechanism which may be applied to each car or train unit; Fig. 3 is a projection of the cams, spring and electric motor mechanism illustrated in Fig. 2; Fig. 4 is a sectional view of the triple valve with its connections; Fig. 5 is a diagrammatic view of modified mechanism embodying the invention; and Fig. 6 is a diagrammatic view representing a further form of mechanism embodying the invention.

The mechanism shown in the drawings, for the purpose of illustrating preferred applications of our invention as contemplated at present, comprises the usual locomotive head light set provided by the steam turbine 1, the direct current generator 2 operated thereby, the conductor 3 leading from the generator to the lamps 4, and the conductor 5 containing the series field 6 leading from the lamps to the generator to complete the circuit, a conductor 7 containing the exciting shunt field coil 8 having its respective ends connected with the conductor 3.

and with the conductor 5, between the lamps 4 and coil 6.

A conductor 9, containing the exciting coil 10, is connected at one end with the conductor 7 between the conductor 3 and the coil 8, and at the other end with the manually operated oscillatory arm 11 of a rheostat whose resistance 11' is connected by the conductor 12 with the conductor 5, between the lamps 4 and the series field coil 6, the arm being connected with and operated by the lever 13 of the brake valve 13'.

The voltage of the generator 2 is maintained at a practically constant value with the headlight on or off, by its compound field 6. The headlight and excitation load on the generator, or the excitation lead alone, will have a definite constant value for each of the various positions of the arm 11 of the rheostat regardless of the number of cars in the train. The rheostat is provided with a scale indicating the positions of the arm 11 for the release, running, holding, lap, service application, and emergency application of the braking mechanism, as by the letters R. R. H. L. S. and E.

A direct current generator 14, driven by the turbine or fluid motor 1 and separately excited from the generator 2 by the coil 10, is connected by the conductor 15 with the ground and by the conductor 16 through the ammeter 17 with the resistance 18 of a master rheostat, the latter having an arm 19 which is connected with the train wire or train wire section 20 on the engine. This master rheostat, in the locomotive cab, may be set so that its resistance plus the resistance of the train line and the ground return is a relatively constant amount, regardless of the number of cars in the train, within the limits of such rheostat.

The ammeter 17 is provided with a scale marked as with the letters R. R. H. L. S. and E., or otherwise as may seem desirable, which will indicate to the engineer the value of the amperes flowing through the train line and whether it is the correct value for causing the apparatus on the several cars of the train to operate the brakes as desired.

Each car or train unit is provided with a train wire or train wire section 20 which is preferably connected at its ends with coupling heads 21 on the hose 22 of the train pipe 23 and the wire is adapted to be connected at the end of each car with the ground by a conductor 24 (the car frame and wheels) through a switch 25 which may be conveniently operated by the adjacent train pipe angle-cock 26, the latter closing the pipe and the switch simultaneously and opening them simultaneously.

As illustrated in Figs. 1, 2, and 3, each car or train unit of the braking mechanism carries an electric "relay" or "motor mechanism" 27 in circuit with and excited by cur-

rent in the wire 20. A circuit 20' around each relay or motor mechanism is controlled by a switch 20'' and serves to cut out such relay or motor mechanism when desired.

The relay or motor mechanism 27 turns 70 a journaled shaft 28 against the action of a coiled spring 29. Cams 30, 31 and 32 are fixed on the shaft 28 and act on the respective rods or stems 33, 34, and 35, which reciprocate in ends of the respective similar 75 cylinders 36, 37 and 38 of the braking unit on the car, the rods having therein the respective vents 33', 34', and 35', and thereon the puppet valves 33'', 34'' and 35''.

The cylinders 36, 37 and 38 contain the 80 respective diaphragms 36', 37' and 38' having therein the ports 36'', 37'' and 38'', controlled by the said valves; the respective diaphragms 36', 37' and 38' which support coiled springs 36'', 37'', and 38'' acting against 85 the said valves; the respective channeled piston valves 36'', 37'', and 38''; the respective coiled springs 36'', 37'', and 38'' supported by ends of the cylinders to act against the piston valves; the respective ducts 36'', 37'', 90 and 38'' extending around the said diaphragms; the respective ports 36'', 37'', and 38'' and 36'', 37'', and 38'' controlled by the said piston valves; and openings 36'', 37'' and 38'' between the diaphragms. 95

The openings 36'', 37'', and 38'' communicate with branches 39'', 39'', and 39'' of a conduit 39 which is connected with the auxiliary reservoir 40. The ports 36'' and 38'' communicate with the atmosphere, while the 100 similarly placed port 37'' is connected by a conduit 41, containing a choke valve 41' and a check valve 41'', with the brake cylinder 42. A branch conduit 43 connects the conduit 41 between the check valve and 105 brake cylinder with the chamber 44' of the triple or universal valve 44 (Fig. 4), this chamber being thereby connected with the brake cylinder. The port 36'' is connected by the conduit 45 with the exhaust port 44'' of the triple valve and the ports 37'' and 38'' are connected with the branches 46'' and 46'' of a conduit 46 which is connected through the conduit 47 (from the brake pipe 23) with the opening 44'' of the triple valve. 110 The conduit 47 contains a cock 47' for cutting off pneumatic communication between the brake pipe and the brake unit. A valve 46' in the conduit 46 and a vent cock 45' in the conduit 45 permit the disconnection from the standard brake equipment of our improved mechanism, if desired for any reason. 120

It will be understood that when the hose coupling heads 21 of the several cars of a 125 train are connected, with the angle cock 26 at the rear end of the train closed and the intermediate cocks open, an electric circuit is thereby closed through the train to the ground by the operations which connect the 130

pneumatic units of the several cars, or that the usual operations for connecting the pneumatic units of the several cars also connect the electric units on the cars which are 5 coördinated with the respective pneumatic units.

The ends of the train, as the engine cab and caboose, may be equipped with any usual 10 form of signaling mechanism 48 connected with the train wire, for transmitting signals.

In operation, an approximately constant 15 resistance will be maintained in the train line circuit, with a variable voltage for the separately excited generator 14, but which voltage is constant for any particular position of the brake valve, and a certain definite current will flow in the train line, depending upon the position of the brake valve handle 13, the latter simultaneously 20 setting the rheostat and the brake valve connected therewith in the desired definite relation, for release, running, holding, lap, service or emergency, according to the corresponding indicia R. R. H. L. S. and E. 25 This current will operate simultaneously and similarly the relays or motor mechanisms 27 of the respective braking units, and the motor mechanisms will turn the respective shafts 28 with the cams 30, 31 and 32 there- 30 on, against the actions of the springs 29, the amount of the like movements of the several sets of cams depending upon the current flowing, which is determined by the position of the handle 13 and is shown by the 35 indicator 17.

Upon the movement of the arm 11 from "release" to "running" position, the cam 30 on the armature shaft 28 moves the rod 33 and the valve 33" of the cylinder 36 to the 40 extreme position, which opens the port 36", whereupon air from the reservoir 40, transmitted by the conduits 39 and 39a to the interior of the cylinder 36 between the diaphragms 36" and 36a, flows through the port 45 36" and passage 36a to the space between the diaphragm 36a and the piston 36a, the latter being moved thereby to bring its channel into registration with the ports 36" and 36a. Exhaust to the atmosphere is thereby established from the brake cylinder 42 through 50 the conduits 43 and 45 which are connected through the triple valve 44, the latter's ports 44a and 44b having been connected as a result of the surge of air admitted to the brake 55 pipe 23 by the movement of the brake valve 13" to release position.

In the release, holding and lapping positions, none of the cams 30, 31 and 32 acts upon any of the rods 33, 34, and 35 to operate any of the puppet valves 33", 34", and 35", which now close their ports 36", 37" and 38", where they are held by the springs 36", 37", and 38"; the springs 36a, 37a, and 38a moving the valves 36a, 37a, and 38a to 60 their inner positions due to the release of air

through the passages 36a, 37a, and 38a and the vents 33", 34", and 35" now connecting them with the atmosphere.

In the service position, the cam 31 moves the rod 34 with the valve 34" thereon to 70 open the port 37", whereupon air flows from the reservoir 40 through the conduits 39 and 39b to the cylinder 37, thence through the port 37" and passage 37a to the space between the diaphragm 37a and piston 37c, the 75 latter being moved thereby against the action of the spring 37d until the channel in said piston connects the ports 37f and 37g. The reduction of air pressure in the brake pipe resulting from the escape of air through 80 the connected pipes 46a and 41 to the brake cylinder causes a movement of the triple valve whereby communication is established between the ports 44d and 44a, permitting air to flow from the reservoir through the 85 pipe 43 to the brake cylinder and apply the brakes.

In the emergency operation, the cam 32 moves the rod 35 with the valve 35" thereon to open the ports 38", which allows air 90 to flow from the reservoir 40 through the passages 39, 39c, 38" and 38a to the space in the cylinder 38 between the partition 38a and the valve 38c, the latter being moved thereby to position establishing communication therethrough between the ports 38f and 38g. Thereby communication is established to the atmosphere from the brake pipe 23 and conduit 47 through the conduits 46, and 46b. The consequent reduction in pressure 100 in the brake pipe effects the operation of the triple valve to connect the reservoir 40 with the cylinder 42 through the passages 44d and 43 and permit a greater flow of air to the brake cylinder than occurs in the service 105 operation.

The modified construction illustrated in Fig. 5 comprises valve mechanism consisting of the cylinder 50 containing the channeled piston 51 which controls the connection between the conduits 45 and 52 (to atmosphere), 46a and 41, and 46b and 53 (to atmosphere). The valve piston 51 is provided with a solenoid armature 54 and coil 55 in the train wire 20, for moving such piston against the action in succession of the coiled springs 56, 57 and 58 which are supported in the end of the cylinder and compressed by the bearing 59 carried by the solenoid core.

When the piston is placed in position by the regulation of the current passing through the coil 55 to connect the conduits 46b and 53, air escapes from the brake pipe 23 and conduit 47 to the atmosphere and the 125 emergency application is effected.

When, by the further regulation of the current passing through the relay or motor mechanism 55, the piston 51 is placed in position for connecting the conduits 41 and 130

46^a, air flows from the conduits 23 and 47 through the conduits 46 and 41, past the regulated choke valve 41' and the check valve 41'' to the cylinder 43. The valve 44 being set thereby, air flows from the reservoir 40 through the conduits 43 and 41 to the brake cylinder 42, which effects the service application, the check valve 41'' preventing reverse flow through the conduit 41.

10 A valve 46' in the conduit 46 and a vent cock 45' in the conduit 45 permits the improved mechanism auxiliary to the standard equipment to be cut out, if desired.

When the current through the coil 55 is further regulated and the valve piston 51 is moved thereby against the action of the springs, it moves to holding and lap position, and therethrough to running and release position. In the latter position, the 15 triple valve is moved by a surge of air through the brake pipe to connect the ports 44^a and 44^b so that when the armature arm is returned to running position and the valve piston 51 connects the conduits 45 and 52, the 20 brake cylinder is connected with the atmosphere through the conduits 43 and 45.

The mechanism illustrated in Fig. 6 comprises the valve chambers 60 and 60^a adapted to communicate through the port 60^b and 25 connected with the respective conduits 45 and 60', the valve chambers 61 and 61^a adapted to communicate through the port 61^b and connected with the respective conduits 46^a and 41, and the valve chambers 62^a and 62^b 30 adapted to communicate through the port 62^b and connected with the respective conduits 40^b and 62'.

Solenoid coils 63, 64 and 65, in the train wire 20, operate their respective armatures 35 63^a, 64^a, and 65^a to control the puppet valves 63^b, 64^b, and 65^b which control the respective ports 60^b, 61^b and 62^b. In this form of the invention, the field rheostat has its "release" contact point connected by a cross 45 wire 11'' with the "holding" contact point, so that the maximum flow of current through the train line is obtained when the engineer's brake handle is in "running position"; sufficient resistance being cut in upon the 50 movement of the handle to "release" position to permit the spring 63^c to overcome the solenoid 63 and close the valve 63^b.

The spring 63^c tends to hold the valve 55 63^b on its seat and springs 64^c and 65^c tend to hold the respective valves 64^b and 65^b open.

When the brake handle is turned to the position for effecting the emergency application, the minimum current is admitted to 60 the train wire and the valve 63^b is held closed while the valves 64^b and 65^b are held open. Consequently air escapes from the brake pipe 23 and conduit 47 through the 65 passages 46, 46^a, 62, 62^a, 62^b and 62' to the atmosphere, which operates the valve 44 to

connect the reservoir 40 with the brake cylinder 42 through the conduit 43, the check valve 41'' preventing reverse flow through the conduit 41.

When the brake handle is turned to the 70 service position, increased current flows through the train wire 20, the release valve 63^b remains closed, the emergency valve 65^b is closed, and the service valve 64^b remains open, permitting escape of air sufficient to 75 cause a service movement of the triple valve and therethrough establishing communication from the auxiliary reservoir 40 to the brake cylinder 42 through the connected passages 44^a, 44^b and 43, thereby applying the 80 brakes.

When the brake handle is set for the lap and holding positions, further current is admitted to the conductor 20 and the valve 64^b is closed by its coil 64, the valves 63^b 85 and 65^b remaining closed.

When the brake handle is moved through running to release position, the surge of air admitted to the brake pipe operates the triple valve to establish communication between the ports 44^a and 44^b, and resistance being cut in the electric circuit through the cross wire 11'' the valve 63^b remains closed. But when the brake handle is moved to the running position, full current is admitted 95 to the conductor 20 and the release valve 63^b is opened, the valves 64^b and 65^b remaining closed. Communication is now established between the brake cylinder 42 and the atmosphere through the connected passages 100 43, 44^a, 44^b, 45, 60, 60^b, 60' and 60'.

A vent 45' in the pipe 45 may be opened to atmosphere and the cock 46' closed if the electrical apparatus, including the relays or motor mechanisms 63, 64 and 65, is not 105 working.

It will be understood that the apparatus to be operated and the functions to be effected by the movements of the puppet valves in the several figures are interchangeable; that is to say, the puppet valves in any figure may be utilized to control the admission of air from an auxiliary reservoir to operate a piston valve which makes and breaks the brake operating communications 115 (as in Fig. 1), or the valves may directly make and break the brake operating communications, (as in Figs. 5 and 6).

Having described our invention, we claim:

1. In an electro-pneumatic brake mechanism, the combination with the connected train pipe, triple valve, auxiliary reservoir and brake cylinder, of valve mechanism connected therewith for effecting the release, the service application and the emergency application of the brake, and means for operating said valve mechanism to effect said release, service application and emergency application, said means comprising a generator, a train wire and motor mechanism op- 120 125 130

erated by current flowing from said generator through said wire to ground.

2. In an electro-pneumatic brake mechanism, the combination with a train pipe and 5 several units each comprising valve mechanism, auxiliary reservoir and brake cylinder connected together and to the train pipe, of valve mechanisms connected with the respective units for effecting the release, service 10 application and emergency application of the corresponding brakes, a generator, a train wire having separable sections connecting said generator to ground, and means in the respective sections operated by current 15 flowing in said wire for simultaneously operating said valve mechanisms last named.

3. In an electro-pneumatic brake mechanism, the combination with a train pipe having, 20 a plurality of separable sections and a plurality of braking units each comprising a triple valve, an auxiliary reservoir and a brake cylinder connected together and to one of said sections, of pneumatic mechanisms connected with the triple valves, auxiliary 25 reservoirs and brake cylinders of the respective units, and electrical mechanism comprising a train wire having separable sections corresponding to the train pipe sections and means operated by current flowing 30 through the respective train wire sections for operating said pneumatic mechanisms.

4. In an electro-pneumatic brake mechanism, the combination with the train pipe, 35 the engineer's valve for controlling the air therein, and pneumatic means connected with said pipe for operating the brakes, of electrical mechanism for controlling said means, said electrical mechanism comprising a generator, a train wire in circuit with said 40 generator, means operated by said valve for regulating the voltage from said generator through said wire, and means for regulating the amperage in said wire.

5. In an electro-pneumatic brake mechanism, the combination with the train pipe comprising sections having coupling heads 45 for connecting them, a valve for controlling the air in said pipe and pneumatic means connected with the respective sections for operating the brakes, of a train wire having sections electrically connected through said heads, a generator connected in circuit with said wire, means for regulating the current discharged by said generator through said 50 wire, and electric motor mechanism operated by current in said wire for operating the several pneumatic means.

6. In an electro-pneumatic brake mechanism, the combination with the train pipe 60 comprising sections having coupling heads for connecting them, a valve for controlling the air in said pipe and pneumatic mechanisms connected with the respective sections for operating the brakes, of a train wire 65 having sections electrically connected by said

heads, a generator connected in circuit with said wire, a rheostat operated by said valve for regulating the voltage delivered by said generator through said wire, means for regulating the amperage flowing through said 70 wire, and electric motor mechanisms operated by current in said wire for operating the respective pneumatic mechanisms.

7. In an electro-pneumatic brake mechanism, the combination with the train pipe 75 comprising sections having coupling means for connecting them, a train wire comprising sections electrically connected through said connected heads, pneumatic mechanisms connected with train pipe sections aforesaid for 80 operating several sets of brakes, electrical mechanisms comprising motor mechanisms connected with train wire sections aforesaid for operating pneumatic mechanisms aforesaid, and means comprising switches for 85 grounding said train wire sections.

8. In an electro-pneumatic brake mechanism, the combination of the train pipe the triple valve connected therewith, and the auxiliary reservoir and brake cylinder connected with the triple valve, of auxiliary 90 means comprising a conduit for connecting the train pipe with the atmosphere, a conduit for connecting the train pipe with the cylinder, valve mechanism for controlling 95 said conduits, and electrical mechanism for controlling said valve mechanism.

9. In an electro-pneumatic brake mechanism, the train pipe provided with a controlling valve, the triple valve connected 100 with the pipe, and the auxiliary reservoir and brake cylinder connected with the triple valve, of auxiliary means for connecting the train pipe with the atmosphere and the brake cylinder to effect the emergency and 105 service application, valve mechanism for controlling said auxiliary means, and electrical mechanism operated by said controlling valve for operating said valve mechanism. 110

10. In an electro-pneumatic brake mechanism, the combination with the train pipe provided with the controlling valve, the triple valve connected with the pipe, and the auxiliary reservoir and brake cylinder connected with the triple valve, of auxiliary 115 means for connecting the train pipe with the atmosphere to effect the emergency operation, for connecting the train pipe with the cylinder to effect the service application, 120 and for connecting the cylinder with the atmosphere to effect the release, and electrical means comprising motor mechanism operating under control of said valve first named for effecting the emergency application, 125 service application and release.

11. In an electro-pneumatic brake mechanism, the combination with an electric generator, a second electric generator operated under control of said generator first named, 130

- a train wire in circuit with said generator second named, a pneumatic braking mechanism, and motor mechanism operating under control of said circuit for controlling the action of said braking mechanism.
12. In an electro-pneumatic brake mechanism, the combination with a fluid motor and a generator operated thereby, of a generator having a field excited by said generator first named, a train wire in circuit with said generator second named, a pneumatic braking mechanism, motor mechanism operating under control of said circuit for controlling the action of said braking mechanism, and means for simultaneously controlling the electric and pneumatic energy in predetermined relation.
13. The combination with a generator, means for exciting the field of said generator, and a rheostat in circuit with said field, of a train wire containing motor mechanism in circuit with said generator, a rheostat through which current flows from said generator to said motor mechanism, and a pneumatic braking mechanism operating under control of said motor mechanism.
14. The combination with a generator having a rheostat in circuit with its field and means for exciting said field, of a circuit energized by said generator, said circuit containing a meter, a rheostat and motor mechanism, and pneumatic braking mechanism operating under control of said motor mechanism.
15. The combination with a fluid motor, a self excited generator operated thereby, a second generator operated by said motor and excited by said generator first named, means for regulating the excitation of said second generator, a train line containing motor mechanism in circuit with said second generator, pneumatic braking mechanism operating under control of said motor mechanism, and mechanism for simultaneously regulating the air for said pneumatic mechanism and the excitation of said second generator.

In testimony whereof we have hereunto set our names this 22nd day of March, 1918.

JAMES RICHARD SLOAN.
HOWARD F. PERRY.
IRVING GOODMAN.
